Primary Examiner — Ryan Harvey

(74) Attorney, Agent, or Firm — Kirton McConkie; Brian Tucker

(57) CLAIM

The ornamental design for a yoga block as shown and described.

DESCRIPTION

FIG. 1 is a top front perspective view of a yoga block showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 4 Drawing Sheets(56)
